UNITED STATES PATENT OFFICE.

HENRY A. CHRISTY, OF KENILWORTH, ILLINOIS.

CAR-DOOR.

1,068,318.

Specification of Letters Patent.

Patented July 22, 1913.

Application filed September 20, 1912. Serial No. 721,339.

To all whom it may concern:

Be it known that I, HENRY A. CHRISTY, a citizen of the United States, residing at Kenilworth, in the county of Cook and State of Illinois, have invented certain new and useful Improvements in Car-Doors, of which the following is a specification.

My present invention relates to improvements in freight cars of a class used for the haulage of grain and other material in bulk, and, more particularly to a novel construction of the sliding doors of box cars adapted for the transportation of grain, as well as various other kinds of freight. In cars of this class, when used for hauling grain, it is necessary either to provide an inner door additional to the outside sliding door, or else to so construct a single door as to afford a tight closure along the margins of the sliding door at the line of the door-posts and floor-sill, and also to provide means for discharging the grain through the sliding door.

An objection attendant upon the usual type of sliding freight car-door is that the doors are usually hung upon tracks secured to the exterior wall of the car, and slide not in planes coincident with the car side, but exterior thereof. In such cases it frequently happens that the guides for the lower edge of the door become broken, the doors swing outwardly, frequently breaking off, and often cause damage by reason of encountering objects along the line of track.

It is the general purpose of my invention to overcome the above-stated objections and others, which are known and well understood, by a simple and economical construction of car-doors of novel form and which are adapted to serve the purpose of affording a suitable tight closure so as to adapt the car to the haulage of grain and the like and also for general purposes of car-doors when used for handling other classes of freight.

To the above ends I provide a single sliding door, preferably supported from its lower edge and suitably guided at its upper edge, and having provisions for effecting a tight closure at the vertical margins of the door so as to prevent the escape of grain or other material carried in the car. To facilitate the discharge of grain and the like, I preferably provide such sliding door with one or more openings, one at the top and one at the bottom, each of which is closed with

wicket doors, and I provide these wicket doors, as well as the principal door, with suitable locking-devices so as to hold them all securely closed and permit their being sealed in order to protect against theft.

In order to avoid the objections attendant upon the mounting of the door outside of the exterior walls, and the damage caused thereby, I recess the side-wall of the car adjacent to one margin of the door-opening for a suitable distance, to provide a pocket or recess to receive the sliding-door. In order to strengthen the side-wall of the car at a point where cut away, I use metal plates suitably conformed to provide interlocks to engage similar hooked metal plates carried by the vertical margins of the door, all to the end that the door may be moved back and forth on its ways and when closed, afford tight joints at the door-posts.

These, and other objects of the invention which will be hereinafter stated and particularly mentioned in the claims, constitute the preferred embodiment of my invention.

My invention will be more readily understood by reference to the accompanying drawings, wherein—

Figure 1 is a side elevation of a portion of a railway car having my novel door applied thereto; Fig. 2 is an enlarged fragmentary section on the line 2—2 of Fig. 1; Fig. 3 is a similar enlarged fragmentary sectional elevation on line 3—3 of Fig. 1; Fig. 4 is a section on the line 4—4 of Fig. 1; Fig. 5 is a section on the line 5—5 of Fig. 1; Fig. 6 is a section on line 6—6 of Fig. 1; Fig. 7 is a fragmentary central longitudinal section; Fig. 8 is a similar view much enlarged over that of Fig. 7; and Fig. 9 is an enlarged fragmentary section on line 9—9 of Fig. 1.

Referring more particularly to the drawings, it will be seen that I provide within the car-side 15, a recess 16, said recess being entirely within the plane of the car-walls. This recess is bounded at one side by a post 17 forming a stop for the door; at the top by a Z-bar 18 which forms a guide for the top edge of the door, and at the bottom, by a plate 19 having an overhanging end 20 and a track 21. The inner wall of the recess is preferably a metal sheet or plate 22, although it may be of wood if desired. I prefer metal in that it will occupy less space. The door opening 23 is provided, as usual, the door opening being bounded at top and

bottom by the members 18 and 19 just described, and at one side by the Z-bar 24. The leg 25 of the bar provides a guide and cover for the free edge of the door when in closed position. The other side of the door-opening is bounded by a channel 26, one leg of the channel projecting out beyond the plane of the plate 22, as shown in Fig. 8, and providing a pocket within which the rear edge of the door is held, as will be later described. It will be noted that by this construction the door may be mounted and moved at all times in a plane within the car-walls, and need not project outside of the walls, as is customary.

I have noticed that in many cases doors and their fastening mechanisms are damaged by contact with exterior objects, either when the car is moving or when on a siding,

20 and to obviate much of this damage, I provide guards or fenders at top and bottom. The top guard is composed of the Z-bar 27 secured at 28 to the upper sill of the car, and being filled with wood 29, if desired.

25 At the bottom the fender is comprised in the plate 19, a block of wood 30 being seated between the overhanging end 20 and the wall of the car. The ends of both upper and lower fenders are curved, as shown in Figs.

30 7 and 8. The novel door of my invention is composed of a plate 31 having upper and lower wickets or small door openings, and being corrugated as at 32 at its middle portion. This corrugation provides the necessary strength and rigidity to the door. The door is provided on its bottom margin with a Z-bar 33, within which is mounted a plurality of rollers 34 which ride on the track

40 21 and support the door. At its upper margin an angle 35 is secured, the free leg of the angle riding in the overhanging edge of the Z-bar 18, thus sealing the top of the door and at the same time permitting it to 45 slide freely. The side edges of the door are provided with small channels 36, while

50 at the rear edge a second channel 37 is provided, one leg 38 of which seats behind the leg of the channel 26 when the door is fully closed. Thus a perfect seal is provided. The wickets in the door are closed by suitable swinging-doors 39, 40, the upper door 39 being hinged on a shaft 41 and adapted to swing downwardly, while

55 the door 40 is hinged on a shaft 42 and is adapted to swing upwardly. These doors are preferably constructed of metal and have their edges beaded or otherwise strengthened, as shown. The upper door 60 is secured by means of a shaft 43 having an angular middle portion 44 adapted to be projected into the path of an angle 45 secured to the free edge of the door. The shaft is provided with an arm 46 to which is connected a rod 47 projecting down-

wardly and having an offset end-portion 48. This end-portion is adapted to be held by a keeper 49, with means for locking or sealing as is usual. The end 48 of the rod is adapted also to seat in the bifurcated upper end 50 of a rocker 51, which rocker is secured to an offset shaft 52. This shaft abuts against the lower free edge of the door 40 and holds same in closed position. The rocker 51 may be held in closed position by means of a pin 53 adapted to be passed through an ear on the keeper 49. The rod is held in lowermost position by means of a pin 54 passed therethrough. It will be noted that the rod extends through the legs of angles 55, 56 arranged at top and bottom of the corrugated portion of the door. These angles serve to further stiffen the door, as well as hold the locking-rod in proper position.

85 The latch for the main door is best shown in Figs. 1 and 9 and comprises a pivoted lever 57, having an extension or projection 58 thereon. This lever is mounted in a housing 59 bolted to the side of the door. The upper end of the lever 57 is bifurcated and is adapted to accommodate an integral pin 60 projecting from the rod 47. Thus, it will be seen that on removal of the pin 54 the rod 47 may be lifted out of engagement first with the lever 57, then the keeper 49 and then the lever 51. While in this position the latch 58 for the door may be moved and the door swung open, or the pin 53 may be removed and the lower door 100 opened, or the upper door alone may be opened, the rod 47 controlling the action of all the fastening-devices.

90 The fender feature of this invention is claimed in this application only in the particular relation to the door and the recessed part of the car wall, as shown and described in this application, while the fender invention *per se* is claimed in my companion application Serial No. 741,050, filed January 9, 1913.

95 A car constructed in accordance with my invention will be found to be durable in service, grain tight at all times, and to prevent the entrance of rain or snow. The 105 use of the fenders or guard-rails overcomes the danger of damage under ordinary circumstances.

100 Modifications in the construction may be made, and such modifications as are within the scope of my claims, I consider within the spirit of my invention.

I claim:

115 1. In a railway-car, the combination of a wall having a door-opening and being of reduced thickness at a point adjacent said opening, a door adapted to close said opening in one position and to seat in said reduced-portion when in open position, said door being substantially flush with the side 120

125 130

of the car, and a fender projecting from the wall of the car and extending longitudinally of the car beneath the door opening and also at one side thereof and adapted to protect said door against damage in its closed and open positions, substantially as described.

2. In a railway-car, the combination of a wall having a door-opening and being of reduced thickness at a point adjacent said opening, a door adapted to close said opening in one position and to seat in said reduced-portion when in open position, said door being substantially flush with the side of the car, and fenders at top and bottom of said door, each fender extending longitudinally of the car across the door opening and also at one side thereof, said fenders being adapted to protect said door against injury

in its closed and open positions, substantially as described.

3. A car provided with a side door opening, the wall of the car being recessed on its outside, said recess being at one side of and communicating with the door opening, a sliding door movable into the recess in the open position of the door, and a door fender projecting laterally from the car and extending longitudinally thereof across the door opening and into and across the width of the recess and constituting a strengthening beam for the recessed part of the car wall.

HENRY A. CHRISTY.
